2,379,440

Lock and cylinder assembly and a means of facilitating disassembly without a special tool or fittings which may be difficult to obtain and which may be required from time to time and to which such means, according to the present invention, is not subject.

121 This invention relates to a lock cylinder assembly and to a lock device which may be used in combination with a lock cylinder assembly, such as the cylinder assembly described in my copending application, Serial No. 437,547, filed April 3, 1942, and issued August 29, 1944, as Patent No. 2,357,004, of which this application is a division.

122 Edward N. Jacobi, Milwaukee, Wis., assignor to the Briggs & Stratton Corporation, Milwaukee, Wis., a corporation of Delaware

123 Original application April 3, 1942, Serial No. 437,547, now Patent No. 2,357,004, dated August 29, 1944. Divided and this application October 9, 1943, Serial No. 505,593.

124 3 Claims. (Cl. 70-377)

This invention relates to the locks and refers particularly to the cylinder and tumblers of the door latch lock shown in Patent No. 2,318,490, issued to E. N. Jacobi, May 4, 1943, and its divisional copending application, Serial No. 437,547, filed April 3, 1942, and issued August 29, 1944, as Patent No. 2,357,004, of which this application is a division.

In lock devices of the type hereunder consideration, as well as in other tumbler locks, it is desirable that the cylinder be removable. Various devices have been employed in the past for removably securing the cylinder in its casing, but in general they all embody a spring pressed detent carried either by the cylinder or the casing and extending across the juncture therebetween to engage with an abutment or shoulder from which the detent must be freed to permit withdrawal of the cylinder.

It is also the practice in tumbler locks of the character described to retain the individual tumbler springs either by individual retainers, or more suitably by means of a single retainer fixed to the cylinder with portions thereof disposed over the tumbler springs. With a view toward minimizing the number of parts, the present invention combines the functions of retaining the tumbler springs and removably holding the cylinder in its casing, this feature being claimed in the aforesaid copending application, Serial No. 437,547.

The specific object of the invention here presented is to provide tumblers designed to cooperate with the lock cylinder and each other to effectuate the desired broad general improvement in lock construction stated to be the objectives of the aforesaid patent and application.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawing illustrates one complete example of the physical embodiment of the invention constructed according to the best mode so far devised for the practical application of the principles thereof, and in which:

Figure 1 is a side view of a lock cylinder equipped with tumblers constructed in accordance with this invention;

UNITED STATES PATENT OFFICE

2,379,440

LOCK DEVICE

Edward N. Jacobi, Milwaukee, Wis., assignor to the Briggs & Stratton Corporation, Milwaukee, Wis., a corporation of Delaware

Figure 2 is a cross sectional view taken through Figure 1 on the plane of the line 2-2; and

Figure 3 is a perspective view of the cylinder per se;

Figure 4 is a perspective view of the combined tumbler spring and cylinder retainer; and

Figure 5 is a perspective view of one of the tumblers.

Referring now particularly to the accompanying drawing, in which like numerals indicate like parts, the numeral 5 designates a cylinder which is preferably die cast and has an open transverse tumbler cavity 6 communicating with a longitudinal keyway 7. The side walls of the cavity have opposite grooves 8 extending across their full width to provide tumbler guideways in which the side edges of the tumblers 9 are slidably received.

At one edge of the cavity the cylinder is formed with bridges 10 which extend across the cavity between the tumbler guiding grooves 8. These bridges, together with a similarly located ledge (not shown) on the inner or rear end of the cavity provide lands in position to collide with spring rests 11 on the tumblers to limit the stroke of the tumblers under action of their springs 12.

The individual tumblers, as best shown in Figure 5, are stamped from flat band stock and have their medial portions recessed or cut out at one edge to provide a key opening 13. The spring rests 11 are projections on the inner edges of the intermediate tumbler portions. These projections are bent back to overlie the intermediate portions so that the springs engaging the

same are adjacent to the intermediate portions of the tumblers to be guided thereby. Displacement of the springs from the rests 11 is prevented by having points on the rests project into the ends of the springs.

Heretofore, the tumbler springs were held in place either by individual retainers or a common retainer secured in the cylinder, but in all instances in the past, the tumbler spring retainers were fixed and generally were staked into the cylinder.

With the present invention, an entirely new form of tumbler spring retainer is employed, and as a result the functions of retaining the individual tumbler springs and also removably securing the cylinder in the casing bore are performed by one unit. For this purpose, a novel combination tumbler spring and cylinder retainer indicated generally by the numeral 14 is provided.

As best shown in Figure 4, this retainer 14 consists of a sheet metal stamping having an elongated

gated bar or strip 15 of a length greater than that of the tumbler cavity and having a plurality of spring seats 16 formed thereon. These spring seats may be roughly defined as teeth bent laterally from one edge of the bar 15 and to guard against displacement of the ends of the springs from these seats, their extremities are bent inwardly as at 17.

To accommodate the retainer 14, the cylinder has an open slot 18 extending along one side of the tumbler cavity and continuing past the front end thereof. This slot receives the flat bar or strip 15 with the front end portion thereof located forwardly of the tumbler cavity.

At its rear end, the strip 15 has a projection 19 which enters a hole 20 in the inner end portion of the cylinder which closes the rear or inner end of the tumbler cavity. In this position the retainer 14 has its spring seats 16 disposed between adjacent tumblers and over the individual tumbler springs and as will be readily apparent, is free to swing on the fulcrum provided by the engagement of the projection 19 in the hole 20.

The retainer is thus substantially floatingly mounted and is free to move toward and from the surface of the cylinder in a direction substantially along the line of thrust of the tumbler springs and as will be obvious the reaction of the tumbler springs tends to swing the retainer outwardly of the cylinder.

This outward motion of the retainer is limited by the engagement of its front end 21 with the inner surface of a cylindrical cap 22 pressed onto the front end of the cylinder.

At its front end portion which lies forwardly of the tumbler cavity, the retainer has a transverse arm 23 extending laterally in the same direction as spring seats 16, and at its extremity the transverse arm is bent down to form a flat portion 24 parallel with the bar and provided with an extension 25 which lies directly opposite the front end portion 21.

This extension 25 like the end portion 21 is engageable with the inner surface of the cap 22, and to guard against binding, the edges of the end portion 21 and the extension 25 which engage the cap lie in a plane normal to the plane of the bar or strip 15, and the location of the

retainer is such that these edges engage the cap at points equidistant from a median longitudinal plane passing through the axis of the cylinder and parallel with the plane of the bar or strip 15.

On the rear edge of the transverse arm 23 is an outwardly bent lip 26. This lip, in the free position of the retainer, projects beyond the surface of the cylinder to be engageable behind a shoulder on the casing in which the cylinder is inserted to thereby removably hold the cylinder in the casing bore.

From the foregoing description, taken in connection with the accompanying drawing, it will be readily apparent that the particular construction of the tumblers as shown and described and their association with the cylinder and the retainer contributes materially to the accomplishment of the general objectives of the invention claimed in the aforesaid Patent No. 2,318,490 and the copending application Serial No. 437,597.

What I claim as my invention is:

1. A tumbler for locks comprising: a substantially flat member having a portion cut away to provide a key receiving recess, said recess dividing the member into intermediate and end sections, said intermediate section having a projection on its recess edge which is bent around and substantially against one flat face of the intermediate section to provide a spring rest in line with said intermediate section.

2. A tumbler for locks comprising: a substantially flat member having an opening therein to permit the passage of a key therethrough; a projection from one edge of the opening bent around to a position adjacent to one flat face of said member and out of the key passage to provide a spring rest without weakening the section adjacent to the key opening.

3. A tumbler for locks comprising: a substantially flat member having parallel side edges; a key passage opening intermediate the ends of said member; and a spring rest formed at the intermediate portion of said substantially flat member from material cut from the key opening whereby said intermediate portion is not weakened more than necessary to produce the key passage opening.

EDWARD N. JACOBI.
